UNITED STATES PATENT OFFICE.

EDWARD P. KING, OF ANDERSON, SOUTH CAROLINA, ASSIGNOR TO THE L. S. STARRETT COMPANY, OF ATHOL, MASSACHUSETTS, A CORPORATION OF MASSACHUSETTS.

COMBINATION SQUARE.

Application filed May 24, 1922. Serial No. 563,392.

To all whom it may concern:

Be it known that I, EDWARD P. KING, a citizen of the United States, residing at Anderson, county of Anderson, State of 5 South Carolina, have invented certain new and useful Improvements in Combination Squares, of which the following is a specification.

This invention relates to combination 10 squares, and particularly to an attachment for preventing the sliding stock or head from being disconnected from the blade. In the use of the combination square it is sometimes desirable to reverse the stock on the 15 blade. Where the stock is completely detachable from the blade, as in the ordinary combination square, the mechanic is apt to drop the stock or the blade while making this adjustment.

20 To the end therefore of providing a combination square in which the stock will be positively prevented from being disconnected from the blade and will yet be capable of reversal upon the blade when desired, I have devised my present invention.

The construction and operation of my device, together with a selected embodiment which well illustrates the principles involved, is described and shown in the accompanying specification and drawings, and the 30 characteristic features of novelty are particularly pointed out in the appended claim. Throughout the specification and drawings like reference numerals are applied, and in 35 the drawings:

Fig. 1 is an elevation of a combination square in accordance with my invention, and showing in dotted lines the stock moved to positions permitting it to be reversed 40 upon the blade.

Fig. 2 is a fragmentary detail, partly in section, particularly illustrating the construction for preventing complete disengagement of the stock and blade, and

45 Fig. 3 is a section on the line 3—3, of Fig. 2.

I have indicated at 1 the graduated blade and at 2 the slidable stock or head of a combination square of standard type. The 50 blade 1 is provided between its edges in one face thereof with the usual longitudinal

groove 3, and the stock or head 2 is provided with the usual clamping bolt 4 engaged in said groove and effective when tightened to hold the adjustment of the stock and blade 55 relative to each other.

According to my invention, the groove 3 terminates short of the ends of the blade in an enlargement 5 which prevents complete detachment of the stock from the blade and permits the stock to be swung about the blade at this point and reversed thereon.

In use, when it is desired to reverse the stock upon the blade, the clamping bolt is loosened by unscrewing the tightening nut 65 6 thereof and the head moved endwise along the blade until the guiding projection 7 of the clamping bolt lodges within the enlargement 5 at the end of the groove. The stock may then be swung about the blade and at 70 this point reversed thereon without bodily detachment therefrom.

Various modifications in the construction and operation of my device may obviously be resorted to all without departing from 75 the spirit of my invention if within the limits of the appended claim.

What I therefore claim and desire to secure by Letters Patent is:—

In combination, a blade having a longitudinally extending groove terminating short of the blade end in an enlarged opening, a stock having a continuous slot in one end thereof permitting said stock to straddle said blade and have continuous bearing 85 thereon throughout the length of the bottom of said slot, said stock being adjustable relative to said blade and having a releasable clamping member provided with a portion disposed for sliding travel in said groove of 90 the blade to permit longitudinal adjustment of the stock relative to the blade and for turning movement in said enlarged opening of the blade to permit the stock to be reversed upon the blade without bodily detachment therefrom.

In testimony whereof I affix my signature in presence of two witnesses.

EDWARD P. KING,

Witnesses:

D. OSBORN,
